UNITED STATES PATENT OFFICE

2,561,039

BOBBY PIN STRIPPING DEVICE

Ruth K. Weaver, Chicago, Ill., assignor to Gaylord Products, Incorporated, Chicago, Ill., a corporation of Illinois

Application May 15, 1948, Serial No. 27,351

5 Claims. (Cl. 254—1)

1

This invention relates to improvements in a bobby pin stripping device and is more particularly concerned with the provision of a device adapted for use in transferring bobby pins from an oven wire to a strip of cardboard.

In the manufacture of bobby pins, they are mounted upon oven wires for operations, such as heat treatment, japanning, baking, etc. After the bobby pins have reached their finished form, it is necessary to remove them from the oven wire, which operation is referred to in this art as a stripping operation.

The present invention contemplates the provision of a relatively simple device adapted to receive an oven wire having a plurality of bobby pins mounted thereon in spaced parallel relation, said device embodying means for engaging and spreading the legs of the bobby pins to permit removal of the oven wire and insertion of a strip of cardboard. The strip of cardboard, with the bobby pins mounted thereon, is then removed from the device for a subsequent carding operation in which, the bobby pins are removed from the strip of cardboard and placed on printed cards suitable for distribution and sale.

This invention further contemplates the provision of a stripping device which is relatively simple in operation, inexpensive in construction and which will not readily get out of order.

This invention embodies other novel features, details of construction and arrangement of parts which are hereinafter set forth in the specification and claims, and illustrated in the accompanying drawings, wherein:

Fig. 1 is an end elevational view illustrating a bobby pin stripping device embodying features of this invention.

Fig. 2 is a top plan view of same.

Fig. 3 is a transverse sectional view taken along the line 3—3 of Fig. 2, showing an oven wire loaded with bobby pins positioned within the device.

Fig. 4 is a transverse sectional view corresponding to Fig. 3 in which, the legs of the bobby pin are shown in spread position, the oven wire removed, and a strip of cardboard positioned between the spread legs of the bobby pin.

Fig. 5 is a detail plan view illustrating the manner in which the bobby pins are mounted upon an oven wire prior to the stripping operation.

Fig. 6 is a detail plan view illustrating the manner in which the bobby pins are applied to a strip of cardboard.

Fig. 7 is an end elevational view of same.

Referring now to the drawings for a better understanding of this invention, the bobby pin stripping device is shown as comprising a pair of end frame members 2—2 which are secured in spaced parallel relation to a table top 3 by any suitable means, such as screws or bolts, not

shown. A back plate 4 is supported at its ends upon the frame members 2—2, and is secured thereto by means of cap screws 6. The back plate 4 is provided with an upturned flange portion 7 for engagement by a plurality of bobby pins 8 mounted upon an oven wire 9, and is also provided with an abutment strip 11 which is secured in position by means of screws 10. The upturned flange 7 and abutment strip 11 are of substantially the same length as the back plate 4.

A fixed bobby pin spreading plate 12 is secured to a shaft 13 journaled at its ends in bearing members 14—14 which extend upwardly from their frame members 2—2. The free end of the spreading plate 12 is bent downwardly at 16 to engage the ends of the uncrimped legs of the bobby pins 8. The spreading plate 12 is provided with a handle, or finger engaging portion, 17 for pivoting the spreading plate 12 from its bobby pin engaging position, illustrated in Figs. 3 and 4, to its inoperative position, illustrated in dotted outline in Fig. 1. When the spreading plate 12 is in its inoperative position, it rests upon a bracket 18 secured to the back plate 4 by means of cap screws 19.

A movable bobby pin spreading plate 19 is secured to a shaft 21 journaled at its ends in a pair of bearing apertures formed at the free ends of a pair of arms 22—22a. The free end of the movable spreading plate 19 is bent downwardly at 23 to engage the free ends of the crimped legs of the bobby pins 8. The movable spreading plate 19 is adapted to be pivoted from its operative position, illustrated in Figs. 3 and 4 to an inoperative position, illustrated in dotted outline in Fig. 1. The arms 22—22a are keyed to a shaft 24 journaled at its ends in the frame members 2—2.

A lever 26 is also keyed to the shaft 24 and has its free end bifurcated to receive one end of a connecting link 27. The free end of the lever 26 and the adjacent end of the connecting link 27 are provided with apertures to receive a bearing pin 28. The lower end of the connecting link is pivotally connected to a foot pedal 29 by means of a bearing pin 31. The foot pedal 29 is mounted for pivotal movement on a pivot pin 32 provided on a pedal base 33, and a compression spring 34 is interposed between the pedal 29 and the pedal base 33 to yieldably resist downward pivotal movement of the pedal. A fulcrum bar 36 is provided to normally engage against the crimped legs of the bobby pins 8, and is supported upon the outer ends of a pair of arms 37—37 which have their inner ends secured in apertures formed in a shaft 38. The ends of the shaft 38 are journaled in bearing apertures formed in the frame members 2—2. A compression spring housing 39 is secured to one of the frame members 2 by means of cap screws 41, and is provided with a cylindrical bore to receive a

compression spring 42. The compression spring 42 engages against a pin 43 provided on the shaft 38, and acts to yieldably resist rotational movement of the shaft 38 in a counterclockwise direction, as illustrated in Figs. 3 and 4. An arm 44 is provided on one end of the shaft 38 for engagement by a pin 46 provided on the arm 22a when the latter is caused to move outwardly and downwardly by downward pressure exerted upon the foot pedal 29.

In the operation of the device thus described and illustrated in the drawings, the spreading plates 12 and 19 are first disposed in their inoperative positions, as illustrated in dotted outline in Fig. 1. The foot pedal 29 is then pressed downwardly to move the fulcrum rod 36 away from the upturned flange 7 of the plate 4. The operator then positions an oven wire 9, with a plurality of bobby pins 8 thereon, in position between the upturned flange 7 and the fulcrum rod 36, the loop ends of the bobby pins being in engagement against the abutment strip 11. The operator then releases the foot pedal 29 to permit the fulcrum rod 36 to move into engagement against the crimped legs of the bobby pins. The fixed spreading plate 12 and the movable spreading plate 19 are then pivoted to their operative position in which their respective downturned flanges 16 and 23 engage the free ends of the legs of the bobby pins 8, as illustrated in Fig. 3. When the foot pedal 29 is moved downwardly, it then passes through the connecting link 27, lever 26, shaft 24, arms 22-22a and movable spreading plate 19 to draw the crimped legs of the bobby pins 8 away from the uncrimped legs. By referring to Fig. 4 in the drawing, it will be noted that the movable spreading plate 19 acts to bend the crimped legs of the bobby pin outwardly about the fulcrum rod 36. To prevent bending the crimped legs of the bobby pins beyond their elastic limits, the compression spring 42 is provided to yieldably resist outward movement of the fulcrum rod 36.

When the legs of the bobby pins 8 have been spread to their open positions, as illustrated in Fig. 4, the oven wire 9 is removed and a strip of cardboard 47 is inserted between the legs of the bobby pins, the forward edges of the strip of cardboard resting upon a pair of shoulders 48-48 provided on the frame members 2-2. The foot pedal 29 is then released to permit the compression spring 34 to act through the connecting link 27, lever 26, shaft 24 and arms 22-22a to return the movable spreading plate 19 to its first position, as illustrated in Fig. 3. The spreading plates 12 and 19 are then pivoted to their inoperative positions, illustrated in dotted outline in Fig. 1. The foot pedal 29 is then moved downwardly to move the fulcrum rod 36 out of contact with the bobby pins 8, and the card 47, with bobby pins thereon, is removed from the device for subsequent carding operations.

While this invention has been shown in but one form, it is obvious to those skilled in the art that it is not so limited but is susceptible of various changes and modifications without departing from the spirit and scope of the claimed invention.

I claim as my invention:

1. In a device for transferring bobby pins from an oven wire onto a strip of cardboard, a bobby pin supporting plate formed with a working face, a fulcrum bar to normally hold a bobby pin

against the working face of said supporting plate, means to move said fulcrum bar away from said supporting plate, a holding plate to engage the free end of one leg of a bobby pin, a spreading plate to engage the free end of the other leg of a bobby pin, and means to move said spreading plate relative to said holding plate to open and close the legs of said bobby pin.

2. In a device for transferring bobby pins from an oven wire onto a strip of cardboard, a bobby pin supporting plate formed with a working face, a fulcrum bar to normally hold a bobby pin against the working face of said supporting plate, means to move said fulcrum bar away from said supporting plate, a holding plate to engage the free end of one leg of a bobby pin, a spreading plate to engage the free end of the other leg of a bobby pin, and means to move said spreading plate relative to said holding plate to open and close the legs of said bobby pin, and resilient means to yieldably resist movement of said fulcrum bar away from said supporting plate.

3. In a device for spreading bobby pins to permit removal of an oven wire straddled by said pins and to permit the disposition of a cardboard strip in straddled position between the legs of said pins, means for supporting a bobby pin carrying a straddled oven wire between its legs, means for spreading the legs of said pin relative to each other to permit removal of said oven wire and the insertion of a cardboard strip between said spread legs, and fulcrum means engageable with the side of a leg of the pin about which said leg is flexed by said spreading means.

4. In a device for spreading bobby pins to permit removal of an oven wire straddled by said pins and to permit the disposition of a cardboard strip in straddled position between the legs of said pins, means for supporting a bobby pin carrying a straddled oven wire between its legs, means for spreading the legs of said pin relative to each other to permit removal of said oven wire and the insertion of a cardboard strip between said spread legs, and fulcrum means engageable with the side of a leg of the pin about which said leg is flexed by said spreading means, said fulcrum means having a substantially convex fulcrum surface.

5. In a device for spreading bobby pins to permit removal of an oven wire straddled by said pins and to permit the disposition of a cardboard strip in straddled position between the legs of said pins, means for supporting a bobby pin carrying a straddled oven wire between its legs, means for moving one leg away from the opposed leg to spread the legs of the pin to permit removal of said oven wire and the insertion of a flat strip between said spread legs, and fulcrum means engageable with the side of said moved leg between the U-bend of the pin and point at which the leg-moving force is applied about which said leg is flexed.

RUTH K. WEAVER.
